UNITED STATES PATENT OFFICE

HARRY C. DREIBUSS AND PAUL J. McCULLOUGH, OF ST. LOUIS, MISSOURI, ASSIGNORS
TO SCULLIN STEEL CO., OF ST. LOUIS, MISSOURI, A CORPORATION OF DELAWARE

FENCE POST

Application filed November 6, 1931. Serial No. 573,380.

This invention relates to fence posts, and is illustrated as embodied in a post having a substantially V-shaped cross-section, and having flanges at the lateral edges, a slight concentration of metal along the horizontal center or vertex, and horizontal ribs spaced vertically along the center line to act at once as fence supporting lugs and as angular reinforcements, or to prevent the spread 10 or cave-in of the legs.

Numerous objects are accomplished by this invention: A post made in accordance with this invention closely approaches the best possible use of the metal, for while using a minimum of metal, it is able to resist extremely severe forces exerted on it in any direction, and it is believed that even considering its poorest angle of attack it is stronger per unit of metal than any post here- 15 tofore known which was of such cross-section, as to render its manufacture by rolling practicable.

In addition, the fence supporting lugs which formerly have been a total waste, 20 structurally speaking, have now been made in the form of transverse, horizontal ribs extending around and beyond the angle of the post, whereby the post is greatly strengthened by preventing the spread or cave-in of the 25 side flanges of the post. An anchor is provided and so arranged that welding is feasible, and the strength of attachment is far greater than is necessary to withstand all forces likely to be exerted on the anchor.

With these and various other objects in view, the invention may consist of certain novel features of construction and operation, as will be more fully described and particularly pointed out in the specification, 35 drawing and claims appended hereto.

In the drawing, which illustrates an embodiment of the device, and wherein like reference characters are used to designate like parts,

Figure 1 is a fragmentary view of the post showing the anchor partially attached;

Figure 2 is a vertical sectional view taken through the center of Figure 1;

Figure 3 is a transverse sectional view 50 taken through the line 3-3 of Figure 1;

Figure 4 is a view showing the entire fence post drawn to a smaller scale; and

Figure 5 is a transverse sectional view taken through the line 5-5 of Figure 1.

Although this invention may take many forms, only one has been chosen for illustration. In this form, the fence post proper is designated by the numeral 10, and the anchor plate by the reference numeral 12. The fence post without the anchor, and except for the ribs, is of uniform cross-section, although of course it is pointed at its bottom end, as shown in Figure 4. This cross-section is shown best in Figure 3, in which it may readily be seen that the fence post includes side members 14, which in the cross-section are the legs of the V. Along the lateral edges of the side members 14 are the flanges 16, which lie in a plane at right angles to them, which may be said to be bisecting the angle of the post. As a matter of accuracy, however, the post has no angle, as the side members 14 are joined to a curved central portion 18. For the sake of convenience, this central portion will be called the angle or the angle portion of the post.

It should be noted that the cross-section of the fence post is for the most part of uniform thickness, but that the center portion 18 is slightly thickened, and this thickening, together with its being in the form of a rather wide curve rather than slightly angular, provides a concentration of metal along the angle of the post to give greater rigidity against forces acting forwardly and backwardly on the post, and also greater durability to withstand the forces exerted by a hammer driving posts into the ground. The flanges 16 not only provide a concentration of metal at the back of the post, to resist the same bending forces as those resisted by the central portion 18, but also strengthen the post against lateral forces, that is, forces at right angles to those described. In other words, it

may be said that the flanges 16 considered together, form compressional members corresponding to the tensile member 18, or vice versa, depending on whether the pressure is forward or back. Likewise, if the pressure is lateral, the flanges 16 alternatively 95 take the place of the central portion 18. 100

act as equal compressional and tensional members.

The structure thus far described, is uniform throughout the length of the post above the pointed portion. In addition to this uniform structure there are provided a plurality of vertically spaced ribs 20, as shown, each of these ribs being thin vertically speaking, but long horizontally, so that they extend around and beyond the angle or central portion 18 of the post. These ribs 20 have a dual function, for they serve both as a means for supporting the fence, and as a means for angularly reinforcing the post. By angular reinforcement is not meant a mere reinforcing of the post against crushing blows, which of course would be extremely rare. It involves also the more important function of strengthening the post in resisting bending in any direction, by preventing the angle from spreading or cave-in.

In order that the fence post may be more securely held in the ground, the anchor plate 12 is provided. This anchor plate is attached in a novel manner, best illustrated in Figure 4. As indicated in that figure, the anchor plate is joined to the post at two points, 22 and 23. At point 22 the joint has been shown as complete, while at the point 23 the step of welding has not been performed and the joint is therefore incomplete. In commercial practice, both points could be welded simultaneously by machine. Prior to welding the anchor plate 12 is punched at both points to the shape shown at 23. As clearly shown, portions 24 are pressed down to form a guard for the welding process, leaving a hole through which the molten metal may contact the fence post, or preferably one of the fence post ribs. The plate is then arc-welded to the post at each of these points, the hole and space within the guards preferably being filled with metal to give an integral structure, such as shown at 22. As the fence post and its anchor thus become one integral structure, the attachment of the anchor is extremely strong and durable. One evident advantage of placing the anchor in the position shown is that a rock or earth wedged between the anchor and the side can lock the post against all lateral movement except in a single direction. The new features of welding help make this arrangement possible.

It is to be understood that many other embodiments of the invention, including some in improved form, will be apparent, and in the course of time more will be devised by those skilled in the art. It is not desired that this invention be limited to the details described, for its scope includes all such forms or improvements as come within the spirit of the following claims, construed as broadly as the prior art will permit.

What is claimed is:

65 1. A fence post, the cross-section of which

is of V type and nearly uniform in thickness, a plurality of thin, horizontally extending ribs spaced at short intervals along the angle of the post and extending around and beyond said angle, whereby said post is angularly reinforced; the basic angle portion, disregarding the ribs, having a vertical section which is substantially straight and uninterrupted throughout its length.

2. A rolled metallic fence post having a cross-section of the V type and comprising a pair of angularly disposed side members joined by a continuous, longitudinally uniform angle portion, said angle portion being angularly reinforced by solid spaced, thin horizontally extending and outstanding ribs connecting said side members.

3. A rolled metallic fence post of the V type in cross-section, comprising a pair of angularly disposed side members, a flange extending from the outer edge of and disposed at an angle to each of said side members, all of said members being of substantially uniform thickness, and a longitudinally uniform central angle portion connecting said side members in a wide curve, said angle portion being only slightly thicker than said side members, and solid thin horizontally extending and outstanding ribs connecting said side members to angularly reinforce said angle portion.

4. A rolled metallic fence post of the V type in cross-section comprising a pair of angularly disposed side members, a flange extending from the outer edge of and disposed at an angle to each of said side members, all of said members being of substantially uniform thickness and a longitudinally uniform central angle portion connecting said side members in a wide curve, said angle portion being only slightly thicker than said side members, and a plurality of solid thin horizontally extending ribs projecting perpendicularly from the front of said angle portion to support a fence, said ribs extending around and beyond said angle portion to reinforce the same.

5. A fence post comprising a rolled metallic column of V shape in cross-section, and an anchor integrally joined to the angular portion of said post and extending from said post in a plane substantially perpendicular to the bisector of the angle of the V.

6. A rolled metallic fence post of V type in cross-section having fence supporting lugs on its angle portion and having a substantially flat anchor extending from said post in a plane perpendicular to the bisector of the angle of the V resting against some of said lugs and integrally secured to said fence post.

7. An angular type of fence post having longitudinal side portions and a longitudinally continuous angle portion and having solid integral fence supporting lugs extend-

ing outwardly from said angle portion and being laterally extended beyond said angle portion and integrally joined to said side portions at spaced points to angularly reinforce said post.

8. An angular type of fence post the side portions of which extend in planes which intersect at approximately right angles, said post being reinforced longitudinally by flanges extending along the outer edges of said side portions, and being reinforced angularly by solid fence supporting lugs formed along and outstanding on the joint between said side portions, and connecting said said portions.

9. A rolled metallic fence post having a cross-section of the V type and comprising a pair of angularly disposed side members joined by a continuous, longitudinally uniform angle portion, said angle portion being reinforced by solid spaced, thin, horizontally extending and outstanding ribs connecting said side members, and an anchor member integrally secured to said lugs at points laterally spaced at least three times the thickness of said side members.

10. An angular fence post having an anchor plate integrally joined to the angle portion of said post along a zone extending laterally at least twice the minimum thickness of the anchor plate, said plate being substantially flat and arranged approximately perpendicularly to the bisector of the angle.

11. A fence post comprising a rolled metallic column of V shape in cross-section, and an anchor rigidly secured to the angular portion of said post and extending therefrom in a plane perpendicular to the bisector of the angle of the V; the space between the anchor and the post being unobstructed except at and close to the angle portion.

12. A fence post comprising a rolled metallic column of V shape in cross-section, and an anchor rigidly secured to the angular portion of said post and extending therefrom in a plane perpendicular to the bisector of the angle of the V; and separated from said angle portion by lugs adapted on other parts of the post to engage a fence.

13. A fence post having a center portion and two side portions extending outwardly therefrom in planes at angles to the general plane of said center portion, and an anchor plate rigidly secured to the center portion, and extending away therefrom at an angle to the adjacent parts of the post; said anchor plate and each side portion being remote from one another at their outer edges and forming a deep unobstructed channel between them.

14. A fence post having a center portion and two side portions extending outwardly therefrom in planes at angles to the general plane of said center portion, and an anchor plate rigidly secured to the center portion, and extending away therefrom at an angle

to the adjacent parts of the post; said anchor plate and each side portion being parallel and remote from one another at their outer edges and forming a deep unobstructed channel between them.

15. A rolled metallic fence post having a cross-section of the V type and comprising a pair of angularly disposed side members joined by a continuous, longitudinally uniform angle portion, said angle portion being reinforced by solid spaced, thin, horizontally extending and outstanding ribs connecting said side members, and an anchor member integrally secured to said lugs at points laterally spaced at least three times the thickness of said side members, said anchor being substantially flat and resting against the outside of some of said lugs to secure maximum spacing between the plate and the side members.

Signed at St. Louis, Missouri, this 30th day of October, 1931.

HARRY C. DREIBUSS.
PAUL J. McCULLOUGH.

16. A fence post having a center portion and two side portions extending outwardly therefrom in planes at angles to the general plane of said center portion, and an anchor plate rigidly secured to the center portion, and extending away therefrom at an angle to the adjacent parts of the post; said anchor plate and each side portion being remote from one another at their outer edges and forming a deep unobstructed channel between them.

17. A fence post comprising a rolled metallic column of V shape in cross-section, and an anchor rigidly secured to the angular portion of said post and extending therefrom in a plane perpendicular to the bisector of the angle of the V; the space between the anchor and the post being unobstructed except at and close to the angle portion.

18. A fence post comprising a rolled metallic column of V shape in cross-section, and an anchor rigidly secured to the angular portion of said post and extending therefrom in a plane perpendicular to the bisector of the angle of the V; and separated from said angle portion by lugs adapted on other parts of the post to engage a fence.

19. A fence post having a center portion and two side portions extending outwardly therefrom in planes at angles to the general plane of said center portion, and an anchor plate rigidly secured to the center portion, and extending away therefrom at an angle to the adjacent parts of the post; said anchor plate and each side portion being parallel and remote from one another at their outer edges and forming a deep unobstructed channel between them.

20. A fence post having a center portion and two side portions extending outwardly therefrom in planes at angles to the general plane of said center portion, and an anchor plate rigidly secured to the center portion, and extending away therefrom at an angle

21. A fence post having a center portion and two side portions extending outwardly therefrom in planes at angles to the general plane of said center portion, and an anchor plate rigidly secured to the center portion, and extending away therefrom at an angle
